A. WHITE.

DEVICE FOR SHAPING GRINDING WHEELS.

APPLICATION FILED MAY 12, 1913.

1,112,104.

Patented Sept. 29, 1914.

UNITED STATES PATENT OFFICE.

ALPHONZO WHITE, OF WORCESTER, MASSACHUSETTS, ASSIGNOR TO NORTON GRINDING COMPANY, A CORPORATION OF MASSACHUSETTS.

DEVICE FOR SHAPING GRINDING-WHEELS.

1,112,104.

Specification of Letters Patent. Patented Sept. 29, 1914.

Application filed May 12, 1913. Serial No. 766,993.

To all whom it may concern:

Be it known that I, ALPHONZO WHITE, a citizen of the United States, residing at Worcester, in the county of Worcester and State of Massachusetts, have invented a new and useful Device for Shaping Grinding-Wheels, of which the following is a specification.

This invention relates to an attachment 10 to be used with surface grinding machines for shaping the cutting surfaces of the grinding wheels thereof to any desired form, as for example, concave, convex, beveled and the like.

15 The principal objects of the invention are to provide a simple, compact and effective shaping device of this character which can be attached to the work table of the grinding machine in a simple way and will work thereon without necessitating the modification of the grinding machine itself in any way.

20 The invention also involves improvements in details of construction and combination 25 of parts as will appear hereinafter.

Reference is to be had to the accompanying drawings in which—

Figure 1 is a transverse sectional view of the work supporting table of a surface 30 grinding machine showing a preferred embodiment of this invention thereon in elevation; Fig. 2 is a plan of the same with the grinding wheel and guard removed; and Fig. 3 is a sectional view on the line 3—3 of 35 Fig. 2.

The attachment is shown as comprising a base 10 which is designed to be secured by T-bolts 11 or in any other desired way to the table A of the grinding machine. This base 40 is provided with two upright arms 12 at one end carrying a pair of studs 13. On these is pivotally mounted a plate 14, movable toward and from the base. On this plate is fixed a holder 15 for the diamond-point 16. 45 or other tool by which the cutting operation is to be performed, and on the bottom of this holder is located a hardened steel bearing piece 17. The plate 14 can be depended upon under certain circumstances to be moved toward the base 10 by gravity, but I prefer to use a spring-pressed rod 18 for keeping the plate down under all circumstances.

On the base 10 are ways 20 on which is 50 mounted a slide 21. On this slide is an ad-

justable arm 22 which is capable of being moved longitudinally of the slide and secured in adjusted position by bolts 23 or the like. This arm is provided with a slot at the end for receiving a screw 24 or the like adapted to be secured to the end of an interchangeable templet or form 25 which moves on a stationary support 26 of hardened steel. This form 25 is provided with a surface 27 which in itself constitutes the 60 guiding means for the hardened steel piece 17 which rests upon it.

Extending out from the side of the slide 21 is an ear 28 having a perforation 29. This receives a pin 30 secured on the end of an arm 31 projecting from a bracket 32. This bracket is secured to the guard B of the grinding wheel C, by screws 33 or in any other desired way.

The operation of the device is very simple. It will be understood, of course, that the table A, being kept in stationary position, the wheel and its guard and shaft D can be moved back and forth as indicated by the arrow in Fig. 1. This can be done by hand 75 while the wheel rotates. Each motion of the guard is transmitted absolutely and accurately to the former 25, and therefore the diamond point 16 follows absolutely the surface 27 and cuts the surface of the grinding wheel to the same shape in cross section. The former 25 positively holds the diamond point in proper position at all points and necessitates the accurate cutting of the wheel. This constitutes a very simple arrangement for cutting down grinding wheels to any desired profile, and it is operated in a very simple and expeditious manner. Moreover, if there is any part of the wheel which requires more cutting than another the operator has this entirely within his control as he can move the wheel back and forth longitudinally of the shaft in any desired way. If he leaves the wheel longer in one position than in another the diamond point cannot cut it any more in that place than elsewhere. An inexperienced operator can cut the wheel to the desired shape as he can keep passing the wheel over the diamond point until he gets no cutting action 100 at any point along the surface of the wheel. The cutting operation is true and accurate under all circumstances, as the spring on the rod 18 keeps the bearing piece 17 always in contact with the templet.

Although I have illustrated and described only one embodiment of the invention and indicated it as applied to only one type of machine, I am aware of the fact that modifications can be made in the construction of the parts and their relative arrangement to each other, and that it can be modified or applied to other types of machines than the one shown, without departing from the scope of this invention as expressed in the claims. Therefore, I do not wish to be limited in these respects, but

What I do claim is:—

1. The combination with a grinding machine having an axially reciprocable rotatable wheel; and a work table, of means for shaping said wheel comprising a plate between the wheel and table; means carried by said plate for shaping the wheel as it rotates, and means movable axially with the wheel for moving said plate and shaping means positively toward the wheel.
2. In an attachment for grinding machines, the combination with a base adapted to be applied to the work table of a grinding machine, of a support for a diamond point located over said base, and movable toward and from the base, and means movable axially with the grinding wheel to be operated upon, and located between said base and support, for controlling the position of the diamond point with respect to the axis of the wheel.
3. In an attachment for grinding machines the combination of a base adapted to be attached to the work table of a grinding machine, of a plate movably connected with said base, a support on said plate for a diamond point or other cutting tool, a slide movable along said base, means for moving said slide with the wheel to be cut, and means movable with said slide for controlling the distance of the diamond point from the axis of the grinding wheel.
4. In an attachment for a grinding machine, the combination with a base adapted to be secured to the work table of the grinding machine transversely thereof, and parallel with the grinding wheel shaft, of a plate between said base and the grinding wheel shaft pivoted to one end of said base on an axis parallel with the surface of the work table, a cutting tool support on said plate, and a member slidable along said base parallel with the grinding wheel shaft and under said support for engaging said

support during its sliding motion and controlling the pivotal motion of said plate.

5. In an attachment for grinding machines, the combination of a base adapted to be secured to the work table of a grinding machine, a plate pivoted to said base at one end thereof and extending over the base, a support on the top of said plate for a cutting tool, and a member slidable along said base under the plate and support and having a master surface engaging the bottom of said cutting tool support.

6. In an attachment for grinding machines, the combination of a base adapted to be secured to the work table of a grinding machine, a plate mounted over said base and movable up and down thereon, a support on said plate for a cutting tool, a member slidable along said base under said support and having a master surface engaging the bottom of said cutting tool support, and a spring carried by said base for holding the cutting tool support down against said master surface.

7. In a device for shaping grinding wheels, the combination with the guard for a grinding wheel movable therewith of a base adapted to be secured to the work table of a grinding machine, a slide movable along said base, a templet supported on said base and movable therewith along with the slide, movable means connected with said base for supporting a cutting tool against said templet, and means for reciprocating said slide comprising a bracket connected with said guard and movable therewith.

8. The combination with a grinding machine, having a work table, a grinding wheel shaft, a grinding wheel, and a guard for the grinding wheel movable along with the grinding wheel, of an arm projecting from said guard and movable therewith, a base secured to said work table, a slide on the base connected with said arm and movable therewith and having a templet connected therewith, and a cutting tool support movably connected with said base in position to be operated by said templet as the slide moves along the base.

In testimony whereof I have hereunto set my hand, in the presence of two subscribing witnesses.

ALPHONZO WHITE.

Witnesses:

CHARLES H. NORTON,
ALBERT TURNER.
